UNITED STATES PATENT OFFICE.

JOHN W. VAN DYKE, OF BROOKLYN, NEW YORK.

STEAM-GENERATOR.

SPECIFICATION forming part of Letters Patent No. 290,502, da'ted December 18, 1883.

Application filed December 14, 1882. (No model.)

To all whom it may concern:

Be it known that I, JOHN W. VAN DYKE, of Brooklyn, in the county of Kings and State of New York, have invented certain Improvements in Steam-Generators, of which the following is a specification.

This invention relates to that class of "sectional boilers," so called, in which the tubes are placed zigzag in vertical or substantially vertical planes with the said tubes, connected at their ends in such manner that circulation of water may be effected from the lowermost to the uppermost tubes of each vertical series, or vice versa.

15 My said invention comprises certain novel means whereby the construction of steam-generators of said class is greatly facilitated, and whereby the expansion and contraction incident to changes of temperature in the boiler 20 is prevented from interfering with the stability of the brick-work ordinarily used in connection therewith.

Figure 1 is a vertical longitudinal sectional view of a steam-generator constructed according to my said invention. Fig. 2 is a front view, and Fig. 3 a rear view, of the same. Fig. 4 is a detail sectional view on a larger scale, showing one of the parts included in the construction of the apparatus.

30 A are the tubes of the steam-generator, which are placed in parallel series, as represented in Figs. 2 and 3, each series being composed of any desired number of the tubes placed one over another in the approximately zigzag relative positions represented in Fig. 1. Thus, for example, one end of the uppermost tube is closely adjacent to one end of the tube next below, whereas the opposite end of the latter is lowered, so as to be brought closely adjacent to the extremity of the tube next below that, and so on to form the zigzag series composed of tubes alternately inclined in opposite directions, as represented in Fig. 1, as aforesaid. The closely-adjacent ends of the tubes of each series are connected by what, for convenience, I term "return-castings," (indicated by the reference-letter B.) These castings, constructed and applied as hereinafter fully set forth, provide communication from the end of one tube to the next adjacent end of the next tube, and so on, as will be understood by reference to said Fig. 1. The construction of the cast-

ings B is represented in the detail view, Fig. 4. Each casting is made of cast-iron, of any suitable quality, and is of substantially rectangular form and hollow or box-like. At the inner side of each casting are two circular holes or openings, a, designed to receive the ends of tubes A, which are fastened therein by expanding by means of a suitable tool. In 55 the outer or opposite side of the castings B are two hand-holes, b, which may be of any size suitable or convenient for the insertion and manipulation of the expanding-tool used in attaching or connecting the ends of the tubes 60 A in the openings a, as hereinbefore set forth. The hand-holes b are closed by plates c, the bolts d of which work in connection with cross-bars or yokes e, placed across the openings b, and resting on the edges thereof in a manner 65 well understood in the art, except that the plate is placed outside and the yoke within. Each casting B has projecting from its outer side lugs f, through which are formed vertical 70 slots a', the slots a' of the one casting being in line with the corresponding slots of the other castings above and below.

C are the ordinary brick walls of a sectional boiler, which form in practice the sides of the fire and smoke space, and which extend upward substantially to the top of the boiler. Extending from one to the other of these walls, at the front and rear of the boiler, are strong girders or beams D, through which are passed vertical suspensory bars E, attached at their 80 upper ends to the girders and extended down between the lugs f of the castings B. Each of the suspensory bars E is transversely slotted at a point immediately below each of the lugs between which it passes, so that keys F, being 85 driven through the said slots, bear upward against the under side of the lugs f, and consequently sustain the return-castings and the attached ends of the tubes, the said parts being suspended from the girder or beam 90 above. The return-castings should be so proportioned that those placed side by side, as indicated in Figs. 2 and 3, will touch each other. When desired, they may be of such sizes and proportions that the upper surfaces of one horizontal set or system of the castings will be in contact with the under surfaces of the set or system above; but, when desired, the said castings may be so proportioned as to leave a space 95 100

between the horizontal sets or systems aforesaid, which space may be filled in with brick, as represented in Fig. 2.

The castings B', in which terminate the forward ends of the uppermost of the tubes A, have fitted into them vertical tubes I, which communicate with a drum, H, by means of the chamber I', formed on or attached to the head of the drum, said drum being placed over the tubular portion of the generator, the said drum at its rearmost end communicating by a vertical tube, N, with a mud-drum, K, which, in its turn, communicates by short vertical tubes or passages h with castings B'', in which are inserted the rearmost ends of the lowest of the tubes A.

In the operation of the apparatus the water, heated by combustion in the fire-box L, and by the passage of the hot gaseous products of combustion through and between the tubes, in a manner similar or analogous to that of the passage of hot products of combustion through the tubes in the ordinary sectional boiler, passes upward to the lowermost of the tubes, thence through the lowermost of the return-castings to the tube next above, and so on forward and backward until it passes into the drum, thence downward to the mud-drum, thence again into the lowermost of the tubes, and so on with a continuous circulation.

By means of the return-castings B, constructed and combined with the tubes, as set forth, I am enabled to provide a sectional boiler capable of being very readily put together without the necessity of handling large castings or relatively heavy pieces of metal, and in which the tubes shall be affixed in place by expanding their ends into suitable holes or openings provided for that purpose in the castings, great convenience being at the same time provided for tightening the tubes in place when they become loose, for affording access to the tubes to clean the same, and for other incidental repairs or attention, there being at the same time such connection of the tubes that the water will circulate through all the tubes of the vertical series, and be thereby exposed to the heat for a relatively great period of time, so that steam is most effectually generated therein, and thence transmitted with the volume of water to the drum at the top of the apparatus. Furthermore, by suspending each of the return-castings separately from a truss or beam overhead, each of the said castings and tubes connected therewith is enabled

to separately adjust itself to any changed condition incident to variations in temperature, so that all rocking of the boiler itself, and especially all tendency to displacement on the part of the walls surrounding the boiler, is avoided. It is to be understood that the suspension of the sections, as aforesaid, may, when desired, be continued or extended, so as to include the suspension of the mud-drum, this alternative being a mere matter of judgment or opinion on the part of the builder. 65

What I claim as my invention is—

1. The combination of the girders or beams D, castings suitably constructed to provide return-passages to the tubes, vertical rods E, 70 hanging from said girders and extending down parallel with and outside of said castings, and forming a support for the same, and tubes arranged in series, each series composed of tubes alternately inclined in opposite directions, the 75 whole constructed, combined, and arranged for joint use and operation substantially as and for the purpose herein set forth.

2. In a steam-generator, the combination of the castings B', constructed to receive the adjacent ends of the upper series of tubes, A, and also the adjacent ends of the vertical pipes I, and having the hand-holes b, with the return-castings B, series of oppositely-inclined tubes A, the series of vertical pipes I, drum 85 H, having chamber I', adapted to receive said pipes I, and the independent pipe N, extended downward from said drum and communicating with the series of tubes A at the lower part thereof, all substantially as and for the 90 purpose herein set forth.

3. The combination, in a steam-generator, of the girder D, a series of pipes connected together by castings B, and a series of rods hanging from said girder, passing down parallel 95 with and outside of said castings, and forming a support for the same, substantially as described.

4. The combination of the girders or beams D, vertical suspensory rods E, keys F, castings B, having lugs f, and the tubes A, arranged in series, each series composed of tubes alternately inclined in opposite directions, the 100 whole constructed, combined, and arranged for joint use and operation substantially as 105 and for the purpose set forth.

JOHN W. VAN DYKE.
